METHOD AND MEANS FOR CONTROLLING THE MOVEMENT OF A TAPE

Application filed March 11, 1926. Serial No. 93,979.

This invention relates to a novel and improved method and means whereby the movement of a tape may be readily controlled by the amount of tape to which it is desired to impart the movement. The invention finds utility in any situation where tape is moved by means of a feeding device, but it finds particular utility in conjunction with a printing mechanism commonly called a ticker which is adapted to print upon and eject a tape.

An apparatus has been devised for projecting upon a screen the tape from a ticker, but certain difficulties have arisen because of the fact that tape is ejected from a ticker with a jerky, intermittent movement, whereas it is highly desirable to have the tape moving smoothly through the projection position from which the quotations are projected on to the screen. This movement has been obtained by employing a tape-moving device to move the tape through the projection position, which device is provided with means giving it a high inertia. This result may be attained by employing a fly wheel or by using a high speed motor or an electric motor having an armature of sufficient size to give the desired effect. The object is to develop a relatively large amount of kinetic energy, whereby the starting and stopping of the tape will be done with a gradual acceleration or retardation and, therefore, the movement of the tape across the screen will appear to be a relatively smooth and continuous one.

According to my invention, I have provided means for starting and stopping the motor by the movement of the tape through the ticker, and this means in conjunction with the employment of a motor having a high inertia results in an arrangement by which the movement of the tape through the projection position is not only a relatively smooth and continuous one but also is controlled automatically.

Referring now to the drawings in which I have shown a selected embodiment of my invention:

Figure 1 is a plan view of a control device employed with my invention.

Figure 2 is a front elevation of the device shown in Figure 1.

Figure 3 is a diagram showing the relation of the various parts used in the practice of my invention.

Referring now to the drawings and particularly to Figure 3 the numeral 1 designates a ticker which may be of any well-known type the details of which are not important so far as my invention is concerned. The ticker acts upon a tape 2 which may be stored upon a supply reel 3 and fed through the ticker in the usual way. The ticker may be provided with the usual pulling rolls 4 and with the usual type wheel 5 coacting with a printing device 6. The rolls 4 pull the tape 2 from the reel 3 and, after the printing device and type wheel print a character on the tape, it is ejected from the ticker in a manner well-known in the art. The tape is then passed through the projection position exemplified by the transparent support 7. The characters on the tape are projected upon the screen 8 by means of light provided from a lamp 9, which light passes through the condenser 10, support 7, tape 2 and objective 11, and is then deflected to the screen 8 by a suitable deflecting means, such as a mirror 12.

I prefer to move the tape through the projection position by means of feed rollers 13 and 14, between which the tape is passed. One of these rollers is driven through suitable gearing 15 by a motor 16. This motor is preferably one having a high inertia and this fact I have indicated by showing the fly wheel 17 mounted on the shaft of the motor. As stated above, however, this fly wheel may be dispensed with and the same effect achieved by employing a high speed motor or one having an armature of a large mass.

Energy is supplied to the motor from a source of current indicated as the line 18 having therein a switch 19. One side 20 of the line to the motor has installed therein the adjustable resistance 21 for a purpose which will presently appear. The other side 22 of the line passes to the motor through a control indicated generally at 23.

This control comprises a base 24 upon which is rotatably journaled a contact wheel 25 which is of conducting material and carries on its periphery a plurality of contacts 26. 5 The space between the contacts 26 is filled with insulating material 27. The side 22 of the line is connected to the binding post 28 of the control and the same post may conveniently hold a spring contact 29 in position to be engaged by the contacts 26 upon rotation of the wheel. A conductor 30 connects the other side of the motor with a binding post 31 upon the base of the machine and through the base of the wheel 25 15 and the contacts 26. The insulating material 27 is preferably cupped out as indicated so as to receive the roll 32 which is mounted upon an arm 33 acted upon by a spring 34, so that the roll 32 releasably holds the wheel 25 in position where the contact finger 29 is out of engagement with any one of the contacts 26.

The tape from the reel 3 is threaded between the rolls 35 and 36, the roll 35 being 25 mounted upon the shaft of the wheel 25. The roll 36 holds the tape 2 in engagement with the roll 35 by means of the spring 37.

In operation the ticker acts upon the tape in the usual manner. The tape is fed to 30 the ticker by means of the rolls 4 and, after the characters are printed thereon, the tape is ejected from the ticker in the usual manner. It will be obvious that the tape in 35 passing to the ticker will cause rotation of the wheel 25. When the ticker is not operating, the circuit to the motor 16 is opened but, as the ticker operates and causes rotation of the wheel 25, the motor circuit will be closed every time that the wheel in its 40 rotation causes a contact 26 to come into engagement with the contact finger 29. The circuit is then immediately reopened. The spacing of the contacts 26 is preferably such that the movement of the tape corresponding 45 to one character printed thereon will turn the wheel 25 through an angle subtended by one contact and one insulating segment. Therefore, the circuit will be closed and opened a number of times corresponding to the number of characters 50 printed upon the tape. By adjusting the resistance 21 it is possible to provide energy to the motor 16 in proportion to the amount of tape which the ticker has ejected and in 55 sufficient amount to exactly take up the tape which has been ejected from the ticker. In any case the amount of energy is proportional to the amount of tape ejected from a ticker or to the number of characters 60 printed thereby.

It is apparent that the motor and the mechanism driven by it are wholly independent of the operation of the ticker but will operate at such a speed that the kinetic 65 energy of the rotating system is proportion-

al to the amount of tape which it is desired to move through the projection position, this amount of tape being determined by the ticker. By employing a motor having a fly wheel effect the starting and stopping of the tape in this movement through the projection position will always lag behind the speed of the tape as it passes through the ticker, the acceleration or retardation being gradual in starting and stopping. Consequently, when considering any given period of time the travel of the tape through the projection position will not necessarily equal the travel of the tape through the ticker for the same period of time, nor will the average speeds be the same necessarily. The result is a change from the jerky and intermittent motion caused by the ticker to a relatively smooth and continuous one.

It will be apparent to those skilled in the art that various changes in the construction illustrated and described may be made without departing from the scope of my invention and I therefore do not intend to limit myself except by the appended claims.

I claim:

1. In combination, a ticker, a tape-moving device for feeding a tape ejected from said ticker through a projection field, an electric motor to operate said device, and means to supply energy to said motor in small increments and in proportion to the amount of the tape to be moved thereby.

2. In combination, a ticker, a tape-moving device for feeding a tape ejected from said ticker through a projection field, an electric motor to operate said device and having a high inertia, and means to supply energy to said motor in small increments and in proportion to the amount of tape to be moved thereby.

3. In combination, a ticker adapted to print and eject a tape, a device to move the tape away from the ticker as it is ejected therefrom and including an electric motor, a circuit including said motor, a wheel having a plurality of contacts on the periphery thereof and adapted to open and close said circuit, and means for rotating said wheel by movement of tape through said ticker.

4. In combination, a ticker adapted to print and eject a tape, a device to move the tape away from the ticker as it is ejected therefrom and including an electric motor, a circuit including said motor, a wheel having a plurality of contacts on the periphery thereof and adapted to open and close said circuit, means for rotating said wheel by movement of tape through said ticker, and means to releasably hold said wheel in position to maintain said circuit open.

5. In combination, a ticker adapted to print and eject a tape, a device to move the tape away from the ticker as it is ejected therefrom and including an electric motor

of high inertia, a circuit including said motor, a wheel having a plurality of contacts on the periphery thereof and adapted to open and close said circuit, and means for 5 rotating said wheel by movement of tape through said ticker.

6. In combination, a ticker adapted to print and eject a tape, a device to move the tape away from the ticker as it is ejected 10 therefrom and including an electric motor of high inertia, a circuit including said motor, a wheel having a plurality of contacts on the periphery thereof and adapted to open and close said circuit, means for 15 rotating said wheel by movement of tape through said ticker, and means to releasably hold said wheel in position to maintain said circuit open.

7. In combination, a ticker adapted to 20 print and eject a tape, a device to move the tape away from the ticker as it is ejected therefrom and including an electric motor, a circuit including said motor, a wheel having a plurality of contacts on the periphery 25 thereof and adapted to open and close said circuit, means for rotating said wheel by movement of tape through said ticker, and an adjustable resistance in said circuit for the purpose set forth.

8. In combination, a ticker adapted to print and eject a tape, a device to move the tape away from the ticker as it is ejected 30 therefrom and including an electric motor of high inertia, a circuit including said motor, a wheel having a plurality of contacts on the periphery thereof and adapted to open and close said circuit, means for rotating said wheel by movement of tape through 35 said ticker, and an adjustable resistance in said circuit for the purpose set forth.

9. The method of controlling movement 40 of a tape ejected from a ticker through projection position, which comprises moving the tape by a device having a high inertia, and periodically supplying substantially 45 equal increments of energy to said device in an amount proportionate to the amount of tape to be moved.

10. The method of controlling movement 50 of a tape ejected from a ticker through projection position, which comprises moving the tape by a device having a high inertia, and supplying energy to said device in small increments and in an amount proportionate to 55 the amount of tape to be moved.

11. The method of controlling movement 60 of a tape ejected from a ticker through projection position, which comprises moving the tape by a suitable device, and supplying energy to said device in small increments and in an amount proportionate to the amount of tape to be moved.

In testimony whereof, I have affixed my signature to this specification.
